UNITED STATES PATENT OFFICE.

JACOB L. KRAUSS, OF JENKINTOWN, PENNSYLVANIA.

DESIGN FOR A CHANGE-RECEPTACLE.

44,535.

Specification for Design.

Patented Aug. 19, 1913.

Application filed May 16, 1913. Serial No. 768,167. Term of patent 7 years.

To all whom it may concern:

Be it known that I, JACOB L. KRAUSS, a citizen of the United States, residing in Jenkintown, Montgomery county, Pennsylvania, have invented a certain new, original, and ornamental Design for a Change-Receptacle, of which the following is a specification, reference being had to the accompanying drawing, forming part thereof.

In said drawing, Figure 1 is a perspective view of a change receptacle showing my new design, and Fig. 2 is a central transverse section further illustrating the invention.

I claim:

The ornamental design for a change receptacle as shown.

In testimony whereof, I have signed my name to this specification, in the presence of two subscribing witnesses.

JACOB L. KRAUSS.
